Primary Examiner — Cynthia Underwood

(57) **CLAIM**

The ornamental design for a sewer hose support, as shown and described.

DESCRIPTION

FIG. 1 is front, top right perspective view of a sewer hose support, folded for storage, according to the invention; FIG. 2 is a front elevational view of FIG. 1 according to the invention;

FIG. 3 is a rear elevational view of FIG. 1 according to the invention;

FIG. 4 is a right elevational view of FIG. 1 according to the invention;

FIG. 5 is a left elevational view of FIG. 1 according to the invention;

FIG. 6 is a top plan view of FIG. 1 according to the invention; FIG. 7 is a bottom plan view of FIG. 1 according to the invention;

FIG. 8 is a front, top right perspective view, unfolded for use, according to the invention;

FIG. 9 is a back, top left perspective view of FIG. 1, unfolded for use, according to the invention; and,

FIG. 10 is a back, top left perspective view of FIG. 1, according to the invention.

The broken lines are included for illustrative purposes only and form no part of the claimed design.
